UNITED STATES PATENT OFFICE.

JAMES LAKE, JR., OF BROOKLYN, NEW YORK.

DESIGN FOR A CROSSBAR FOR MOTOR-CYCLE HANDLEBARS.

Application filed January 18, 1928. Serial No. 24,914. Term of patent 7 years.

To all whom it may concern:

Be it known that I, JAMES LAKE, JR., a citizen of the United States, residing at 1133 East 14th Street, Brooklyn, New York, have invented a new, original, and ornamental Design for Crossbars for Motor-Cycle Handlebars, of which the following is a specification, reference being had to the accompanying drawing, forming part thereof.

The figure is a perspective view of the cross bar.

I claim:

The ornamental design for a crossbar for motorcycle handlebars substantially as shown.

JAMES LAKE, JR.
